UNITED STATES PATENT OFFICE.

EDWIN J. ARMSTRONG, OF ERIE, PENNSYLVANIA, ASSIGNOR TO BALL ENGINE COMPANY, OF ERIE, PENNSYLVANIA, A CORPORATION OF PENNSYLVANIA.

STEAM-ENGINE.

1,168,045.

Specification of Letters Patent. Patented Jan. 11, 1916.

Application filed January 20, 1915. Serial No. 3,370.

To all whom it may concern:

Be it known that I, EDWIN J. ARMSTRONG, a citizen of the United States, residing at Erie, in the county of Erie and State of Pennsylvania, have invented new and useful Improvements in Steam-Engines, of which the following is a specification.

This invention relates to steam engines and consists in certain improvements in the construction thereof as will be hereinafter fully described and pointed out in the claims.

More particularly the invention relates to the type of engine which is especially useful in connection with steam power shovels. The moving parts of engines of this type are subjected to severe conditions because of the dust necessarily present as an incident to the operation of the shovel. At the same time the usual type of construction of these engines has made it difficult to inclose them.

The object of the present invention is to provide an inclosing means capable of use with engines of the type specified.

The invention is illustrated in the accompanying drawings as follows:

Figure 1 shows a plan view of the engine, a part of the inclosing cover piece being broken away to better show construction. Fig. 2 shows a side elevation of the engine. Fig. 3 a section on the line 3-3 in Fig. 1. Fig. 4 a section on the line 4-4 in Fig. 1.

1 marks the cylinder, 2 the steam chest, 3 the crank shaft, 4 the crank, it being understood that these are in pairs, the second crank being similar to the crank 4 but on a quarter relatively to said crank, and 5 the connecting rod. The connecting rod is journaled on the crank in the ordinary manner and pivotally connected with the cross head 6. The cross heads are carried by the cross head guides 7 and 8 and these are carried by the frame 9. The eccentric rods 10 operate from the eccentric (dotted lines Fig. 1) and convey movement to the rock levers 11. The rock levers are carried by a rock shaft 12. It will be understood that the second cylinder has a duplication of the mechanism shown in the broken away part in Fig. 1. Valve rods 13 extend from the rock lever to the steam chest. It will be noted that these valve rods move in the same general direction as the cross heads but are off-set from the cross heads in a direction at right angles

to the pivotal connection between the cross head and the connecting rod 5, in other words, the valve mechanisms with the engine placed as shown in the drawings are above the cross head guides 8. The eccentric rods 10 extend from the crank shaft to the levers 11 conveying the movement to the off-set rods. The engine frame has the sides 14 and these are connected by the horizontal webs 15 in which the cross head guides are placed. The frame is open at the sides of the cross heads at 16 and inclosed by cover plates 17. Webs 18 extend upwardly from the webs 15 and the bearings 19 for the rock shafts 12 are arranged in these webs. The wall 14 is carried down on a slant from a position adjacent to the bearings 19 so that the edge of the walls 14 are adjacent to the crank shaft bearings 20. A cover piece 21 co-acting with the frame completes the inclosure of the working parts, the joint 22 at the upper edge of the web 18 at 23 along the upper edge of the wall 14 being formed with the cover. By carrying the webs 18 up from the transverse webs 15 the part between the fixed part of the inclosing walls and the removable cover is such as to permit the bearings 19 to be in the fixed part of the inclosing walls.

Where the engine is used as especially adapted for steam shovel work it is provided with a controlling valve, the stem 24 of which is between the valve rods 13. It is connected by the links 25 with the rock levers 26. The rock levers 26 are arranged on the shaft 27 and the shaft 27 is arranged in the bearings 28. This bearing also is arranged in the web 18 so as to be in the fixed part of the inclosing means. It will be readily observed that while all parts of this engine are readily accessible by this construction of frame and cover all parts may be entirely inclosed.

What I claim as new is:

1. In a steam engine, the combination with the moving parts comprising a cross head; a crank; a connecting rod pivotally connected with the cross head and journaled on the crank; a valve rod moving in the same direction as the cross head and off-set from the cross head at right angles to the axis of the pivotal connection between the connecting rod and the cross head; and an eccentric rod driving the valve rod from the crank shaft; of cross head guides; crank

shaft bearings; a frame on which the guides and bearings are carried; and devices co-acting with the frame inclosing said working parts.

5. In a steam engine, the combination with the moving parts comprising two cross heads; two cranks; connecting rods between the cross heads and the cranks, said connecting rods being pivotally connected with the 10 cross heads and journaled on the cranks; engine valve rods moving in the same general direction as the cross heads and off-set from the cross heads at right angles to the axis of the pivotal connections between the 15 cross heads and the connecting rods; eccentrics driving the valve rods from the crank shaft; a controlling valve rod between the engine valve rods; and means for actuating the controlling valve rod; of cross head 20 guides; crank shaft bearings; a frame on which the guides and bearings are carried; and devices co-acting with the frame inclosing said working parts.

3. In a steam engine, the combination 25 with the moving parts comprising a cross head; a crank; a connecting rod pivotally connected with the cross head and journaled on the crank; a valve rod moving in the same general direction as the cross head and off-set from the cross head at right angles to the axis of the pivotal connection between the cross head and the connecting rod; a 30 rock arm from which the valve rod is driven; a rock shaft on which the rock arm is mounted; and an eccentric rod for driving the rock shaft from the crank shaft; of cross head guides; crank shaft bearings; bearings for said rock shaft; a frame on which the guides and bearings are mounted; 35 and a cover piece co-acting with the frame inclosing said working parts, the joint between the cover piece and the frame forming the part of the inclosure immediately adjacent to the bearings in the frame. 40
- 45 4. In a steam engine, the combination with the moving parts comprising two cross heads; two cranks; connecting rods pivotally connected with the cross heads and journaled on the cranks; engine valve rods

moving in the same general direction as the 50 cross heads and off-set from the cross heads at right angles to the pivotal connection between the cross heads and the connecting rods; rock levers to which the valve rods are connected; a shaft on which the rock 55 levers are mounted; eccentric rods driving the rock levers from the engine shaft; a controlling valve rod between the engine valve rods; a rock lever to which the controlling valve rod is connected; a rock shaft on 60 which the rock lever controlling the controlling valve rod is mounted; of cross head guides for said cross heads; crank shaft bearings; bearings for said rock shafts; a frame on which the guides and bearings are 65 mounted, said frame having inclosing webs extended to form the inclosing walls adjacent to said bearings; and a cover piece co-acting with said inclosing webs to inclose said working parts.

5. In a steam engine, the combination with the moving parts comprising a cross head; a crank; a connecting rod pivotally connected with the cross head and journaled on the crank; a valve rod moving in the 75 same general direction as the cross head and off-set from the cross head at right angles to the axis of the pivotal connection between the cross head and the connecting rod; a rock arm from which the valve rod is 80 driven; a rock shaft on which the rock arm is mounted; and an eccentric rod for driving the rock shaft from the crank shaft of an engine frame having side walls carrying the crank shaft bearings; lateral webs carrying the cross head guides; side webs extending from the lateral webs and having bearings for the rock shaft; and a cover piece co-acting with the side walls and side webs for inclosing the working parts.

In testimony whereof I have hereunto set my hand in the presence of two subscribing witnesses.

EDWIN J. ARMSTRONG.
